(57) **CLAIM**

The ornamental design for a hairdryer, as shown and described.

DESCRIPTION

1. Hairdryer

1.1 : Front

1.2 : Back

1.3 : Left

1.4 : Right

1.5 : Top

1.6 : Bottom

1.7 : Perspective

1.8 : Perspective

1.9 : Perspective View in Folded Status

1.10 : Perspective View in Folded Status

Our new design is related to a hairdryer for drying and/or styling hair; The design characteristic lies in the shape and the reproduction 1.7, i.e., perspective view 1 best shows the design characteristic; The design may be folded into an alternative position, i.e., in a folded status; Reproductions 1.9 and 1.10 are the perspective views of the design in the folded status.
